[57] **CLAIM**

The ornamental design for a global positioning system receiver with offset shape, as shown.

DESCRIPTION

FIG. 1 is a front plan view of a global positioning system receiver with offset shape, showing the design;

FIG. 2 is a right side elevation view thereof;

FIG. 3 is a top elevation view thereof;

FIG. 4 is a left side elevation view thereof;

FIG. 5 is a back plan view thereof; and,

FIG. 6 is a bottom elevation view thereof.

The broken line showing is for illustrative purposes only and forms no part of the claimed design.
